DISPLAY FIGURE

William J. Sweeney, Belleville, N. J.

Application April 3, 1937, Serial No. 134,822

5 Claims. (Cl. 40—126)

The invention disclosed herein relates to display figures for advertising, amusement and other purposes.

Special objects of the invention are to produce the balancing effect of a "tight rope" or "slack wire" performer or to provide a dancing or jumping effect in figures used for display purposes and to accomplish such results in highly attractive forms with relatively simple inexpensive structure.

Further special objects are to provide display apparatus of the character outlined in knock-down shape, which can be packed and shipped in compact form and be quickly and easily set up in a practical self-sustaining structure at the point of display.

Additional objects and the novel features constituting the invention are set forth and will appear in the course of the following specification.

The drawings accompanying and forming part of the specification illustrate different practical embodiments of the invention, but it should be understood that the structure may be modified and changed in various ways all within the true intent and broad scope of the invention.

Fig. 1 is a front view of an embodiment of the invention depicting a performer balanced on a "tight rope".

Fig. 2 is a side elevation of the same.

Fig. 3 is a rear elevation.

Figs. 4 and 5 are broken detail views as taken substantially on the planes of lines 4—4 and 5—5 respectively of Fig. 3.

Fig. 6 is a broken detail illustrating the connection of the wires with the supported figure.

Figs. 7 and 8 are front and edge views respectively of a second embodiment of the invention.

Fig. 9 is a broken plan view of the same.

Fig. 10 is an enlarged broken sectional detail as on substantially the plane of line 10—10 of Fig. 7.

The first embodiment of the invention is representative of the figure of a "tight rope" performer balanced on a wire 12, extending between supports 13.

This figure and supports may be made of flat sheet material, such as suitable cardboard and the whole be foldable, so that it may be readily knocked down for shipment or set up for display.

In this particular illustration, the supports 13 are shown as connected by an intermediate portion 14, hingeable along a vertical line 15. Fixed on the back of one of these relatively hinged sections is shown a base piece 16, Fig. 3, having

hingedly attached edge portions 17, which project beyond the hinge line 15, crossing back of the other section of the base, where they are caught by extending through slots 18, in a securing tab 19, hingedly attached to said second base section as indicated at 20. Fig. 4 shows how when the side strips 17 are turned back from the first base piece and the ends of the same are caught in the securing flap 19, on the back of the other base piece the two portions of the base will be held extended and the hinge connection between the two be braced and secured relatively rigid.

The base, secured in the extended relation described is shown supported in a slightly backward inclined relation by easel strips 21, hingedly secured at 22, on the backs of the support or tower portions 13, which are indicated as caught in the rearwardly outstanding relation by flaps 23, hinging down from the base portions 22, in through openings 24, in the easel props 21 and slotted to engage over the edges of such props as shown at 25, Figs. 2 and 3.

The effect of a figure balanced on the wire is attained in the construction illustrated by making the wire in two sections 12a and 12b, having angularly turned outer ends 26, extending down through receiving openings in the pairs of rearwardly projecting lugs 27, at the back of the supports 13, and angularly turned inner ends 28, meeting and entering a receiving socket 29, in the back of the figure.

The anchorage lugs 27, for the ends of the two piece wire are shown in Fig. 5, as hinged tabs on the upper and lower ends of base pieces 30, secured over the base portions 22, of the braces or props 21, perforated in vertical alignment to take the downwardly extending ends 26 of the wire pieces. The socket 29, for the inner ends of the wire pieces is shown as a downwardly opening recess on the back of the leg of the figure of a size to snugly receive the upwardly extending end portions of the wire, thus locating the junction of the two wire pieces behind the foot of the figure, with the substantially horizontal portions in alignment and having the appearance at the front of a single continuous wire.

The anchorage of the angled outer ends of the wire pieces prevents them from turning and the anchorage of the figure on the upturned inner ends of the wire pieces secures this figure in an upstanding relation, appearing as balanced on a length of supporting wire. The resiliency of the wire causes apparent balancing and back and forth swinging movements of the figure with

vibrations, producing a life-like similitude of a tight rope performer's actions. The torsional or twisting movements of the wire pieces may be governed or controlled to an extent by the material, size and temper of the wire and by the weight and height of the figure, so that various desired back and forth swaying effects may be accomplished.

The wire anchorage lugs 27, are shown as held 10 in their extended positions by having the ends of the same projected through slots 31, in the braces or props 21. The base construction described folds substantially flat yet may be quickly set up in firmly supporting relation. After being so set 15 up, the downwardly angled ends of the wire pieces may be passed down through the openings provided for them in the anchorage lugs 27, and the figure be mounted by simply forcing the socket portion firmly down over the abutted upwardly angled inner ends 28, of the wire pieces. In this 20 assembled relation, the parts are all firmly connected and well braced, but the wire pieces are left in a more or less tensioned springy condition, subject to the slightest vibration to set the figure 25 moving in simulation of a balancing act.

In the second illustration of the invention, a figure 11a, such as representative of an animal, is resiliently supported on a wire 12c, in a position suggesting a dancing or jumping action over a 30 background or support 13a.

In this particular construction, a single piece of wire 12c is employed, having a downwardly angled lower end 12d, entered in a pocket 32, on the back of the support, said wire extending from 35 this bent lower end rearwardly, upwardly and forwardly in a wide loop and terminating in an upwardly projecting angled end 12e, engaged in a pocket 33, on the back of the figure. The wire in this case is tensioned by the weight of the figure and with sufficiently resilient wire, a wide sustaining 40 loop and the proper weight of figure, comparatively slight vibrations will cause the figure to dance or jump over the face of the background, which in the case of an animal may represent a field, possibly with a fence over which the animal 45 may appear to jump. This construction may well be used to provide the illusion of a figure suspended in air, such as an adagio dancer at the top of her leap, etc. The wire, where it is exposed, as it 50 is in the first form of the invention, may be colored the same as the background, making it invisible or less noticeable. In the second form of the invention, the wire may be entirely concealed

and arranged to suspend the figure in a "floating" relation in front of the background or base structure.

The invention may be carried out in a great many ways and the claims should be interpreted 5 accordingly, the terms employed being used in a descriptive rather than in a limiting sense, except as possible limitations may be imposed by the state of the prior art.

What is claimed is:

1. In display apparatus, a figure having a downwardly opening socket on the back of the same, spaced supports having upwardly opening sockets on the back of the same and wire pieces having upwardly angled ends engaged in said 15 downwardly opening socket of the figure and downwardly angled ends entered in said upwardly opening sockets on the support.

2. In display apparatus, supporting wire having downwardly angled ends and upwardly angled 20 intermediate portions, a support having spaced parts receiving said downwardly angled ends and a figure resiliently supported on the wire and having a socket receiving said upwardly angled intermediate portions of said supporting wire. 25

3. Apparatus for providing the illusion of a figure balancing on a wire, comprising spaced supports, wires having angled ends held in said spaced supports and extending in alignment 30 toward each other across the space between said supports, the adjacent ends of said aligned wires being angled and a figure engaged over said last mentioned angled ends, forming a connection between and concealing said angled ends of the wires. 35

4. Display apparatus, comprising an upstanding support, a wire having an angled end engaged in the back of said support and extending rearwardly therefrom in a wide loop projecting upwardly and forwardly toward the front of the 40 support and a figure engaged on the upper end of said wire over the face of said support.

5. Display apparatus, comprising an upstanding support, a wire having an angled end engaged in the back of said support and extending rearwardly 45 therefrom in a wide loop projecting upwardly and forwardly toward the front of the support, a figure engaged on the upper end of said wire over the face of said support, the upper end of said wire being angled and said figure having a socket 50 fitting said angled end.

WILLIAM J. SWEENEY.
